UNITED STATES PATENT OFFICE

2,498,290

ABDOMINAL SUPPORT

Harry Morrison, Pittsburgh, Pa.

Application September 4, 1947, Serial No. 772,110

8 Claims. (Cl. 2—312)

1

This invention pertains generally to abdominal supports and more particularly to those which simultaneously serve for suspending an outer garment and retain an inner one.

My previous invention, patented October 9, 1945, Patent No. 2,386,708, discloses such support. The present invention constitutes a further improvement in abdominal supports inasmuch as it obviates the disadvantages heretofore inherent to devices of this kind, namely the difficulty of their cleaning, laundering, application and upkeep.

Hence one object of the present invention is to provide an abdominal support, outer garment suspender, and inner garment retainer, the directionally rigid attachment means of which are held in pockets on the belt portion of the support, and are easily insertable into, and removable from, the pockets without any sewing, buttoning, or other operation whatsoever.

Another object of the invention is to provide a device of the character described, in which the connecting means between the outer garment and belt portion comprise hooks having an elongated leg portion that is slidingly held in pockets of the belt.

Still another object of the invention is to provide an abdominal support in which the connecting means between the outer garment and belt portion comprise hooks having an S-shaped portion continued by an elongated leg portion extending substantially through the whole width of the belt.

Yet another object of the invention is to provide an abdominal support in which the connecting means between the outer garment and belt portion comprise hooks which are substantially rigid in their longitudinal direction and resilient in a direction vertical thereto.

Another object of this invention is to provide a belt of the type described in which a flexible strip adapted to be attached to the outer garment is provided with a plurality of latches suitable to engage hooks held in pockets of the belt, transferring thus the weight of the outer garment upon the hooks and the belt.

A further object of the invention is to provide an abdominal support that has a plurality of inserted hooks which substantially extend through the whole width of the belt and are rigid in the direction of the belt width and resilient in a direction vertical thereto.

Yet another object of the invention is to provide an abdominal support in which attachment means are held in longitudinal pockets extend-

2

ing in the direction of the width of the belt and open at one end and closed at the other.

Another object of the invention is to provide an abdominal support of the character described which is simple in its structural combination, convenient to wear, can be readily applied, easily taken apart, laundered and is inexpensive to manufacture.

To the accomplishment of these and such other objects as may hereafter appear the invention consists of the novel construction, combination and arrangement of the structure hereinafter described and illustrated in the accompanying drawings showing the embodiments of the invention.

In the drawings, wherein like numerals of reference designate same parts throughout the several views,

Figure 1 is a partial side elevational view of the flexible strip adapted to be fastened to the inside of the outer garment and carrying a plurality of latches.

Figure 2 is a fragmental side elevational view to a larger scale of the strip, illustrated in Figure 1, showing one latch and its fastening, viewed from the side toward the wearer.

Figure 3 is the same fragmental view as shown in Figure 2 but viewed from the opposite side.

Figure 4 is a cross sectional view on line 4—4 in Figure 3.

Figure 5 is a cross sectional view on line 5—5 in Figure 1.

Figure 6 is a side elevational view of the belt portion of the invention showing five supporting hooks inserted into the five pockets as viewed from outside of the wearer.

Figure 7 is a side elevational view of a hook to a somewhat enlarged scale.

Figure 8 is a perspective view of the hook shown in Figure 7.

Figure 9 is a cross sectional view to a larger scale taken at any of the lines 9—9 in Figure 6.

Figure 10 is a perspective view of a second preferred embodiment of my invention in which the hooks are formed of one piece of suitably bent resilient round wire.

Figure 11 is a perspective view of the third preferred embodiment in which the supporting hooks are formed from one piece of suitably bent flat resilient strip.

Referring closer to the numerals of reference in Figures 1 to 9 of the drawings, 12 represents the outer garment of the wearer such as a pair of pants of men or women, or a skirt, etc., of a woman, to which at suitable locations around

the waist region the flexible strip 13 is fastened by sewed seams 14 or by other suitable attachment means, such as buttons, etc. (not shown). A plurality of suitably spaced latches 15 are fastened by suitable means such as webs 16, shown fastened to strip 13 by seams 17. Latches 15 have holes 18 provided for threading through them webs 16, the ends of each of which are then brought together and sewed to strip 13 by seams 17 as previously mentioned above and clearly illustrated in Figure 4.

As best shown in Figure 4 latches 15 have a central flat portion 19 and two flat side portions 20 which are parallel and the latter bearing the holes 18, through which web 16 is threaded.

Strip 13 has for each latch two suitably spaced cuts 21 through which latches 15 are inserted so that flat side portions 20 are between strip 13 and the outer garment 12 while flat side portions 19 are inside toward the wearer.

As seen also in Figure 4 gaps 22 are formed by flat portions 19 of latch 15 and strip 13 which gaps serve for receiving the supporting hooks held in the belt portion as hereinafter described.

As shown in Figure 6 the belt portion of the support consists of a relatively wide belt 23 made of strong fabric which may or may not be elastic. This belt which is to be attached around the waist of the wearer is provided with known fastening means, such as buckles 24, at one end portion, and straps 25, with suitable holes, at the other.

Belt 23 is provided with pockets 26 which are formed by attaching strips of fabric 27 to the belt by seams 28. These pockets 26 are extending across the width of belt 23 and are open at the top and closed by seams 28 on the sides and at the bottom. Suitably spaced pockets 26 are shown but it will be understood that any suitable number of them may be employed. The number of the pockets 26 and their locations correspond to those of latches 15, fastened to strip 13.

Hooks 29 are slidingly accommodated in pocket 26. Hooks 29 have an S-shaped top portion 30 to which a U-shaped resilient wire leg portion 31 is attached. Leg portion 31 and hook portion 30 are both substantially rigid in longitudinal direction but are resilient in a direction normal thereto and the width of the leg portion 31 is such that it slidingly fits into pockets 26 in which they are inserted deep enough so that the inner side of hook portion 30 engage the top portion of belt 23.

The flat portions 19 of latches 15 cooperate with hooks 29 as hook portions 30 are inserted into gaps 22. Hooks 29 may be made of metal, plastic, fishbone, or other resilient materials.

As best shown in Figure 9 in the abdominal support, when worn, leg 31 of hook 29 is inserted in pocket 26 so that hook portion 30 slides into gap 22 of latch 15 and at the same time engages the top portion of belt 23 so that outer garment 12 is held by strip 13, the attached latches 15 lifted by hook portion 30 of hook 29, the leg portion 31 of which is securely held by pocket 26 of belt portion 23. The under-garments such as shirt or blouse 32 and underwear or lingerie 33 are held securely to the body 34 by belt 23.

The operation of the first embodiment of my device is as follows:

Strip 13 with latches 15 is fastened by seams or buttons, etc., to the inner side of the outer garment to be worn. Then belt 23, with hooks 29 inserted in its pockets 26, is tightened on the

wearer around the waist region and finally the latches 15 are slipped into hook portions 30.

The second embodiment of my invention is the same as the first except that each hook, as shown in Figure 10, is made integral from one piece of resilient round spring material.

The third embodiment is the same as the second one except that the hooks are made of flat strip material, as shown in Figure 11.

The operation of the second and third embodiments are the same as that of the first, hence it needs not to be repeated.

Having fully disclosed my invention and described and illustrated three preferred embodiments thereof it will be understood that various changes and modifications may be made therein by those versed in the art without departing from the spirit and scope of my invention, hence I do not intend to be limited by these exemplary embodiments but what I claim as new and wish to secure by Letters Patent is:

1. A garment suspending belt and abdominal support comprising a belt adapted to cover the body areas to be supported, adjustable fastening means on said belt for tightening said belt around the body of the wearer, pockets suitably spaced around said belt, hook means having a resilient leg portion thereon adapted to be removably inserted into said pockets, said hook means projecting outwardly from the belt away from the body of the wearer, a flexible strip attached to a garment to be suspended, latch means on said strip, suitably spaced thereon to correspond with the pockets, said latch means adapted to engage removably the hook means in the pockets of said belt whereby said outer garment is suspended.

2. A garment suspending belt and abdominal support comprising a flexible belt adapted to cover the body areas to be supported, adjustable fastening means on said belt for tightening said belt around the body of the wearer, a plurality of spaced apart pockets along said belt extending transversely of the length of said belt, hook means having a resilient leg portion removably inserted in said pockets, said hook means projecting outwardly from the belt away from the body of the wearer, a flexible strip attached to a garment to be suspended, a plurality of latches spaced apart on said strip at positions corresponding to the position of the pockets on the belt, said latch means adapted to engage removably the hook means in the pockets of said belt whereby said outer garment is suspended.

3. A garment suspending belt and abdominal support comprising a flexible belt adapted to cover the body areas to be supported, adjustable fastening means on said belt for tightening said belt around the body of the wearer, a plurality of spaced apart pockets along said belt extending transversely of the length of said belt, said pockets being open along the side adjacent the top of said belt, hook means having a resilient leg portion inserted removably in said pockets, said hook means projecting outwardly from the belt away from the body of the wearer, a flexible strip attached to a garment to be suspended, a plurality of latches spaced apart on said strip at positions corresponding to the positions of the pockets on the belt, said latch means adapted to engage removably the hook means in the pockets of said belt whereby said outer garment is suspended.

4. A garment suspending belt and abdominal support comprising a belt adapted to cover the

body areas to be supported, adjustable fastening means on said belt for tightening said belt around the body of the wearer, pockets spaced apart around said belt, hook means removably inserted in said pockets, said hook means including a resilient leg portion removably inserted in said pockets and an S-shaped hook portion, one arm of which is fastened to the resilient leg portion and the other arm of which forms an upwardly opened engaging portion, a flexible strip attached to a garment to be suspended, latch means spaced apart on said strip at points corresponding to the pockets on the belt, said latch means adapted to pass over the upwardly opened engaging portion of the hook means in the pockets of said belt whereby said outer garment is suspended.

5. A garment suspending belt and abdominal support comprising a belt adapted to cover the body areas to be supported, adjustable fastening means on said belt for tightening said belt around the body of the wearer, pockets spaced apart around said belt, hook means removably inserted in said pockets, said hook means including a U-shaped resilient leg portion of material of substantially circular cross section removably inserted in said pockets, the ends of the legs of said U-shaped leg portion being fastened to one arm of an S-shaped hook portion of flat strip material, said hook portion having its other arm turned upwardly forming an upwardly opened engaging portion, a flexible strip attached to a garment to be suspended, latch means spaced apart on said strip at points corresponding to the pockets on the belt, said latch means adapted to pass over the upwardly opened engaging portion of the hook means in the pockets of said belt whereby said outer garment is suspended.

6. A garment suspending belt and abdominal support comprising a belt adapted to cover the body areas to be supported, adjustable fastening means on said belt for tightening said belt around the body of the wearer, pockets spaced apart

- around said belt, hook means removably inserted in said pockets, said hook means including a U-shaped resilient leg portion, the ends of the legs of said U-shaped portion being bent to form S-shaped hook portions, said hook portions projecting outwardly from the belt away from the body of the wearer to form upwardly opened engaging portions, a flexible strip attached to a garment to be suspended, latch means spaced apart on said strip at points corresponding to the pockets on the belt, said latch means adapted to pass over the upwardly opened engaging portions of the hook means in the pockets of said belt whereby said outer garment is suspended.
- 10 7. A garment suspending belt and abdominal support according to claim 6 in which the latch means includes generally U-shaped members the ends of whose legs are bent outwardly in a plane parallel to the bottom of the U, each of said outwardly bent portions having a hole therein, and fastening means passing through said hole for fastening the leg to the flexible strip.
- 15 8. A garment suspending belt and abdominal support according to claim 6 in which the latch means includes generally U-shaped members the ends of whose legs are bent outwardly in a plane parallel to the bottom of the U, each of said outwardly bent portions having a hole therein, and a web strap passing through said hole, the ends of said strap being sewn to the flexible strip.
